UNITED STATES PATENT OFFICE.

ROLAND L. BREWER, OF HARTFORD, CONN., ASSIGNOR TO THE COLTS PATENT FIRE-ARMS MANUFACTURING COMPANY, OF SAME PLACE.

BREECH-LOADING FIRE-ARM.

SPECIFICATION forming part of Letters Patent No. 279,324, dated June 12, 1883.

Application filed April 2, 1883. (No model.)

To all whom it may concern:

Be it known that I, ROLAND L. BREWER, of Hartford, in the county of Hartford and State of Connecticut, have invented a new Improvement in Magazine Fire-Arms; and I do hereby declare the following, when taken in connection with the accompanying drawings and the letters of reference marked thereon, to be a full, clear, and exact description of the same, and which said drawings constitute part of this specification, and represent, in—

Figure 1, a longitudinal sectional side view, the parts in the closed or normal portion; Fig. 2, the same with the parts in the open or charging position; Fig. 3, a transverse section on line *x-x*, looking to the rear; Figs. 4, 5, and 6, detached views at the forward end of the barrel, illustrating the method of securing the magazine.

20 This invention relates to an improvement in magazine fire-arms, with special reference to that class in which a breech-piece is arranged to move longitudinally toward and from the open rear end of the barrel and in axial line therewith, operated by a lever below, and in which a carrier for the transfer of cartridges from the magazine to a position in rear of the barrel and forward of the open breech-piece is hung or hinged at the rear, so as to vibrate 25 up and down on that hinge as its center of motion.

In the usual construction of this class of arms either the carrier itself serves as a latch or holder to retain the column of cartridges in the magazine while it (the carrier) is rising to transfer the cartridge which has passed from the magazine onto it to a position in line with the barrel, or, as in other cases, a latch has been provided, which has been actuated by the carrier. From such arrangement a serious difficulty has been experienced, arising from the fact that when a cartridge has been partially forced into the barrel by the forward movement of the breech-piece the carrier descends 40 to receive a second cartridge from the magazine, and if, as it frequently happens, before the previous cartridge has been fully forced to its place in the barrel the breech-piece be withdrawn, another cartridge has passed onto the carrier, and in the ascent of the breech-piece this ascending cartridge will strike the

head end of the previous cartridge and choke or clog the arm, requiring peculiar manipulation to remove the obstruction.

The object of the first part of my invention 55 is principally to overcome this difficulty, and it consists in a dog arranged in the receiver in rear of and substantially below the magazine and in the path of the operating-lever in the closing movement of the breech-piece, whereby 60 said operating-lever will depress said dog and release the column of cartridges in the magazine, and so soon as the movement of the lever to open the breech-piece begins said dog will rise to a position to block the cartridges 65 in the magazine and independent of the carrier; and the invention also consists in details of construction, as more fully hereinafter described.

A represents the receiver; B, the barrel; C, 70 the magazine in the usual relation to each other; D, the breech-piece, arranged to move toward and from the rear open end of the barrel, and in axial line therewith; E, the trigger-guard lever, hung upon a pivot, *a*, the upper 75 arm, F, of said lever in connection with the breech-piece, whereby the downward and forward movement of said lever E imparts a rear and opening movement to the breech-piece, and vice versa, in substantially the usual manner for this class of arms.

G is the carrier, hung upon a pivot, *b*, at the rear, and so as to swing up from the position seen in Fig. 1 to the position seen in Fig. 2, whereby a cartridge which has passed onto the carrier, as seen in broken lines, Fig. 1, is transferred to a position between the front face of the breech-piece and the open end of the barrel, and so that when the breech-piece is closed it will force the said cartridge forward from the carrier into the barrel, also in the usual manner. When the breech-piece is in its closed position a downwardly-projecting lug, *d*, stands in rear of the head of the rear cartridge, H, in the magazine, as seen in Fig. 1. When the parts 95 are in this condition the carrier stands in its down position, ready to receive the said cartridge H, and as the breech-piece commences its rear movement the cartridge H follows against the lug *d* until it arrives to its position on the carrier, as indicated in broken lines, Fig. 1. The front face of the lug *d* is

in rear of the front face of the breech-piece equal to about the thickness of the flange of the cartridge.

In the receiver, and substantially below the magazine, the dog L is hung upon a pivot, e, at the rear, its front end or nose being free to rise or fall, as from the position in Fig. 1, to that in Fig. 2, and return. A spring, f, is provided, the tendency of which is to lift and hold the dog in its up position, as seen in Fig. 2, but yielding for the descent of the dog, as seen in Fig. 1.

In the closing movement of the trigger-guard lever its upper arm, F, strikes the dog L—say as at h—and forces the dog down to bring its nose below the line of the magazine, as seen in Fig. 1, so that when the parts are in their closed position the dog has no effect or control upon the cartridge in the magazine. The carrier has a longitudinal slot, i, (see Fig. 3,) in which the dog L is free to move up and down. When the parts are in their closed position, as seen in Fig. 1, the head of the rearmost cartridge stands over the forward end of the dog L and against the lug d. Then when the lever is turned to open the breech-piece the arm F leaves the dog free to rise against the cartridge, which follows the lug d onto the carrier. When the cartridge has passed onto the carrier so as to bring its forward or smaller diameter over the nose of the dog, then the dog rises and comes into a position in rear of the next cartridge, and so that that next cartridge will abut against the end of the dog, as seen in Fig. 2, and in broken lines, Fig. 1, and this blocking of the column of cartridges next in advance of that cartridge which is passing onto the carrier, will occur before the carrier begins its ascent, and thus the column is blocked independent of the carrier. The carrier is caused to rise by a shoulder, l, coming against a corresponding shoulder, m, on the carrier, as seen in Fig. 2, and this ascent of the carrier begins as soon as the breech-piece has passed so far to the rear that the cartridge may pass up forward of the front face of the breech-piece—that is to say, the carrier rises during the last part of the opening movement of the breech-piece. As the breech-piece moves forward in the closing movement, its front inclined end, n, strikes an inclined shoulder, u, on the carrier, and thereby forces the carrier downward. The under side of the breech-piece passes over the part of the carrier forward of the shoulder n and holds the carrier in its down position, as seen in Fig. 1. This downward movement of the carrier occurs during the last part of the movement of the lever in closing and locking the breech-piece. This construction and arrangement of the dog independent of the carrier, and operated by the arm F of the lever during the last part of its closing movement, prevents the possibility of a cartridge passing onto the carrier, or in any way moving from its place in the magazine until the operative parts of the arm shall have been brought to their completely-closed or normal position.

The object of making the front face of the lug d in rear of the front face of the breech-piece is that when the dog is depressed in the closing movement of the parts, the head of the rearmost cartridge in the magazine may pass to the rear over the dog so far as to prevent the dog rising when the opening movement commences, and thereby interfering with the movement of the cartridge onto the carrier.

It is often desirable to use a magazine-arm as a breech-loader independent of the magazine, or for the purpose of reserving the cartridges in the magazine. For this purpose the carrier must be out of the way, and so as not to interfere with the insertion of the cartridge through the upper opening in the receiver directly into the chamber. To insure the proper position of the carrier for such single or breech-loading purposes, I arrange a spring-pawl, o, at the rear of the carrier, and provide the carrier with notches r and s, these notches being arranged relatively to the nose of the pawl, so that when the carrier is in its extreme up position the nose will engage the forward notch, s, and thereby hold the carrier in its up position while the breech-piece is moving forward to force the cartridge from the carrier into chamber in the barrel, the spring of the dog yielding for the descent of the carrier. The second notch, r, is in rear of the notch s, and in a position so that when the carrier is partially raised, and in a position to serve as a guide for the cartridge to the chamber, the dog o will engage the notch r, as indicated in broken lines, Fig. 2, and there hold the carrier for such charging. It will be understood that this engagement with the notch r is made in the opening movement of the breech-piece, and before the carrier has been fully raised, the pawl o offering a sufficient resistance to indicate when that position is attained.

The peculiar construction of the carrier and its mode of operation in connection with the breech-piece are substantially that found in the patent granted to Andrew Burgess, December 7, 1880, No. 235,204. I use this arm for illustration as a matter of convenience; but it will be understood that the dog L is operated by the lever through which a reciprocating movement is imparted to the breech-piece, and the up-and-down movement to the carrier may be applied to other magazine-arms in which a similar breech-piece is employed in combination with a carrier moving up and down to transfer the cartridges. I therefore do not wish to be understood as limiting the use of the dog L to the particular arrangement of the mechanism of the arm described.

The second part of my invention relates to an improvement in the attachment of the magazine to the arm, the object being to make the attachment such that the magazine may be readily secured or removed; and it consists in a groove cut in the under side of the barrel in the segment of a circle, on a radius considerably shorter than the length of the magazine, and of dovetail or equivalent shape, combined

with a stud fitting into said groove, and a recess in the forward end of the magazine corresponding to and so as to set upon said stud, with a screw or equivalent devices to secure the end of the magazine to said stud, the segment shape of the groove serving to hold the stud in place and prevent transverse movement of the stud when the magazine is attached, as more fully hereinafter described.

o Upon the under side, near the forward end of the barrel, I cut a groove, P, in a horizontal plane parallel with the horizontal plane of the barrel, and segment-shaped, the radius of the segment short—say as seen in Fig. 4. This groove I undercut in dovetail or equivalent shape, as seen in Fig. 5. Into this groove I fit a stud, R, having a base T-shaped, corresponding to said groove P and so that the stud may be passed into said groove from one side until it arrives at a central position, as seen in Fig. 6. This stud stands at the point where the forward end of the magazine C is to come, and the stud is narrower than the diameter of the magazine, as seen in Fig. 6. The forward end of the magazine C has a notch cut into it, corresponding to said stud, as seen in Figs. 5 and 6. When the stud has been set to its place in the groove P the magazine is introduced, its rear end set into its place, as at U, Fig. 1, then its forward end forced onto the stud, as seen in Fig. 5, and through that end of the magazine a screw or other suitable securing device, W, is introduced, which secures that end of the magazine to the stud. When thus in place the stud is prevented from transverse movement, because in such transverse movement the magazine must turn upon its seat U as its center of motion, and that center is so far distant from the center from which the groove P is cut that any tendency to turn the forward end of the magazine to the right or left will be resisted by the shorter arc or circle of the groove P, and thus the magazine will serve to hold the stud in its place in the groove. This construction or method of securing the stud avoids the interlocking devices between the stud and the barrel heretofore necessary.

I claim—

1. In a magazine fire-arm, the combination of a breech-piece, carrier, and lever for operating the same, with the dog arranged in rear of the magazine, independent of the carrier, depressed in the closing movement of the lever to release the column of cartridges, and left free to rise in the beginning of the opening movement of said lever, substantially as described. 50

2. In a magazine fire-arm, the combination of a longitudinally-moving breech-piece, a carrier hinged at the rear, and so that its forward end moves up and down, a lever hung below the breech-piece and in connection with said breech-piece, and whereby said breech-piece and carrier are operated, with a dog, L, 60 hung in the receiver in rear of the magazine, below the carrier, but independent of the carrier, the arm F of the said lever arranged to depress the said dog in the last part of its closing movement, and to release the said dog in 65 the first part of its opening movement, substantially as described.

3. In a magazine fire-arm, the combination of a longitudinally-movable breech-piece, a carrier hung at the rear beneath said breech-piece, and a stop, substantially such as described, independent of the breech-piece and operating-lever, to engage and support said carrier midway between its up and down positions, substantially as and for the purpose 75 so described.

4. In a magazine fire-arm, the combination of a longitudinally-movable breech-piece, a carrier hung at the rear beneath said breech-piece, and constructed with notches r s on its 85 hub, and the pawl o, substantially as described.

5. In a magazine fire-arm, the barrel constructed with the segment-shaped groove P near its forward end, combined with the stud R, constructed with a base, T, corresponding 90 to said groove in the barrel, and the magazine constructed at its forward end for engagement with said stud, substantially as described.
